VENTILATING WINDOW MECHANISM

Burton S. Floraday, Toledo, Ohio, assignor to
Automobile Ventilation, Inc., Detroit, Mich., a
corporation of Michigan

Application February 6, 1935, Serial No. 5,197

19 Claims. (Cl. 268—126)

This invention relates to ventilating windows and more particularly to a system of window ventilation adaptable for embodiment in vehicle bodies such as the doors of automobiles.

An object of the invention is to provide an improved, relatively simple and economical mechanism for raising and lowering the window glass in the body or door or other structure and for providing a ventilating slot at one upright edge of the glass when the latter is substantially fully raised, the preferred construction being such that the window glass may be shifted horizontally or edgewise in its plane into and out of position to provide and/or close said ventilating slot.

A further object of the invention is to provide an improved ventilating window mechanism operable in the manner and for the purposes above described and also having means for shifting the glass edgewise in its plane or longitudinally during the vertical or upward and downward movement of the glass whereby the rear edge of the glass during its vertical travel will clear an obstruction, such as the latch spindle carried by the rear pillar of a door. In accordance with this aspect of the invention the mechanism is particularly adaptable for use in a vehicle door which is hinged at its forward edge and in which the window glass is first shifted vertically into ventilating position and then forwardly to close the ventilating opening.

Embodiments of the invention are shown by way of illustration in the accompanying drawings, in which:

Figure 1 is a side elevation of a portion of an automobile door viewed from the inside with the upholstering removed and showing the window in its closed position;

Figure 2 is a fragmentary view showing the window moved rearwardly to provide a ventilating slot and showing the upper end portions of the regulator arms;

Figure 3 is a view similar to Figure 2 showing the position of the parts after the window has been lowered a short distance from its uppermost position;

Figure 4 is an enlarged sectional elevation on the line 4—4 of Figure 1;

Figure 5 is a vertical sectional elevation on the line 5—5 of Figure 1;

Figure 6 is a sectional view on the line 6—6 of Figure 5;

Figure 7 is a side elevation of a portion of an automobile door viewed from the inside showing

an alternate form of window-operating mechanism;

Figure 8 is an enlarged fragmentary elevation showing the position of the parts just below their uppermost position;

Figure 9 is an enlarged sectional view on the line 9—9 of Figure 8;

Figure 10 is an enlarged sectional view on the line 10—10 of Figure 8;

Figure 11 is a fragmentary elevation showing the position of the parts after the window has been moved rearwardly to provide a ventilating slot;

Figure 12 is a view similar to Figure 11 showing the window partially lowered and moving at an angle; and

Figure 13 is a diagrammatic view showing the path traversed by the window from its raised position with the slot closed to its lowered position.

Referring to Figures 1 to 6 of the drawings, the vehicle door 10 has the usual window opening 11 at the upper portion thereof and window 12, which is guided in its vertical movements by vertically disposed runways or channels 13 and 14. The runway 13 is relatively narrow, whereas the runway 14 is relatively deep. The runway 14 extends from its upper end downwardly to a point below the window opening 11, where it inclines downwardly and forwardly as indicated at 15, and thence downwardly, as indicated at 16. This offset in the runway 14 affords ample clearance for the spindle 17 for operating the door latch (not shown), a handle 18 being disposed on the outside of the door and mounted on the outer end of the spindle 17 for actuation thereof.

Mounted on the lower edge of the window 12 is a channel strip 19, and between the channel strip and the window is a suitable packing 20. Fixed to one side of the channel strip 19 are rails 21 and 22 forming horizontal elongate guide channels in which pins 23 and 24 are adapted to slide. The pins 23 and 24 are mounted on the upper ends of regulator arms 25 and 26 respectively, and secured to the lower end of the arm 25 is a gear sector 26', which meshes with a similar sector 27 mounted on a plate 28 having a larger sector 29 with which a pinion 30 meshes. The pinion 30 is operated by a suitable handle (not shown) disposed on the inside of the door, and these parts are carried by a mounting plate 31 secured in place in any appropriate manner. A spiral spring arrangement 32 is mounted on the pivot pins of the 55

gear sectors for counterbalancing the weight of the window in the usual manner.

Secured to the upper end of the regulator arm 25 is a finger-like extension 33, which projects forwardly and then inclines downwardly providing a tapering depending portion 34 and forming an upwardly and rearwardly curved surface 35, which terminates at its upward end in a notch 36. From the notch 36 the underside 10 of the extension inclines downwardly and rearwardly toward the arm 25, as indicated at 37.

Secured to the upper end of the regulator arm 26 is a member 38 having horizontally disposed inclined surfaces 39 and 40, which are vertically spaced, as particularly shown on Figure 4. Secured to the forward end of the rail 21 is a pin 41, which, for reasons hereinafter described, is disposed in advance of the channel portion of the rail 21, and mounted on the forward end 20 of the rail 22 is a pin 42. The pins 41 and 42 project outwardly from the rails in the path of movement of the finger 33 and the cam member 38.

The operation of the above mechanism is as follows:

Assuming that the window is in its raised position with the ventilating slot closed, as shown in Figure 1, the handle is moved to actuate the pinion 30, which, through the gearing above described, moves the regulator arms 25 and 26 in opposite directions away from each other. The notched portion 36 of the finger extension 33 is in engagement with the pin 41 so that upon movement of the regulator arm 25 to the right (Figure 1), the window 12 is caused to move to the right or rearwardly of the vehicle so that the front vertical edge of the window is moved out of the channel 13 and the rear vertical edge is moved into the relatively deep channel 14 substantially, as shown in Figure 2. This provides a slot V between the front vertical edge of the window and the window frame, and through which foul air, smoke, gases, etc. may be drawn from the inside of the vehicle while the vehicle is in motion, as will be readily understood by those skilled in this art.

It will be understood that the window 12 is guided in such horizontal movement by the pins 23 and 24 riding in the channels provided in the rails 21 and 22, respectively. When the window 12 has nearly completed its horizontal or transverse movement, and due to the angularity of the regulator arm 25, the finger extension 33 is moved so that the notch 36 clears the pin 41 whereby subsequent swinging movement of the arms 25 and 26 in opposite directions causes the window to move vertically downward.

Such movement continues until the inclined portion 15 of the channel 14 is reached, whereupon the member 38 which, in effect, is a cam member, has reached the pin 42. Owing to the angularity of the surfaces 39 and 40, the window 12 is caused to move at an angle downwardly and forwardly, as indicated in Figure 3, following substantially the path indicated by the line 43, such angular motion of the window 12 continuing until the member 38 of the regulator arm 26 has cleared the pin 42. It will be apparent that the finger-like extension 33 serves to prevent the window 12 from being moved forwardly during the downward movement of the window 12 from its uppermost position to substantially the inclined surface 15, the pin 41 abutting against the inner edge 35 of the ex-

tension, thereby insuring that the window remains in the desired position.

Upon movement of the regulator arms 25 and 26 in a direction opposite to that above described, it will be apparent that the above operation is reversed. Mounted in the rear end of the channel 21 is a pin 70, which engages and cooperates with the pin 23 on the arm 25 when the glass 12 is fully lowered for insuring that the pin 42 is properly positioned relative to the member 38 during the raising of the window.

For the purpose of removing the window 12 from its frame and to enable the same to be mounted in position, a block 44 has an elongate slot 45, into which a stud 46 projects. Opposite ends of the block 44 are grooved to fit the pins 41 and 23 respectively. As shown most clearly in Figure 6, the block 44 is positioned adjacent the pin 41 with the pin 46 disposed at the extreme left hand end of the slot 45. In this position the right hand end of the block 44 limits the swinging movement of the arm 25, but by removing the pin 41, which is in screw threaded engagement with the rail 21, the block 44 can be slid to the left, thereby allowing the pin 23 to be moved out of the channel in the rail 21. The right hand end of the channel in the rail 22 is open so that by moving the arms 25 and 26 closer together the pins 23 and 24 can be moved out of engagement with their respective rails to allow the window 12 to be removed.

In the form of the invention shown in Figures 7 to 13, similar gear mechanism is employed, but it will be noted that the regulator arm 25a has a plate extension 47, which extends forwardly, the outer end portion inclining downwardly and forwardly, having fingers 49 and 50 providing a notch 51 therebetween. As shown in Figure 9, the finger 49 is offset inwardly from the finger 50. The regulator arm 26a has a substantially L-shaped cam member 52 secured to the outer end thereof, a portion of which extends rearwardly. The member 52 has a cam surface on its outer edge including abutment portions 53 and 54.

Carried by the outer end of the regulator arm 25a is a stud 55 engaging in a slot 56 formed in a rail 57, which is secured to and depends from the window channel 18a. Mounted on the outer end of the regulator arm 26a is a stud 58, which engages in a slot 59 formed in the rail 57. The slot 59 has a forward horizontally disposed portion and a rearward upwardly inclined portion 60 terminating in an enlarged opening 61. The slot 56 extends in a horizontal direction, but at the forward end portion it extends vertically, as indicated at 62, and then horizontally terminating in an enlarged opening 63. Engageable by the finger extension 49 is a pin 64 secured to the rail 57, and engageable by the finger 50 is a pin 66 also carried by the rail 57, the pin 66 extending outwardly therefrom a greater distance than the pin 64.

The cam member 52 is engageable with pins 66 and 67 carried by the rail 57. The pin 67, as indicated on Figure 10, extends outwardly from the rail 57 beyond the pin 66. Also as indicated in Figure 10, it will be noted that the cam projection 53 is disposed closer to the rail 57 on the abutment surface 54 to enable the abutment surface 54 to clear the pin 66 during the swinging movement of the arm 26a.

As indicated by the lines 68 on Figure 13, the mechanism shown in Figures 7 to 13 imparts similar movement to the window as the mecha-

nism shown and described in connection with Figures 1 to 6. With the parts arranged as indicated in Figure 7 with the window in its raised position, and the ventilating slot closed, it will be noted that the pin 55 is disposed in the upwardly extending portion 62 of the slot or guide channel 56 so that the window is in locked position, any force exerted against the window to move it horizontally being resisted by the pin 55 and regulator mechanism. Upon actuation of the pinion 33 to move the regulator arms 25^a and 26^a in opposite directions, it will be apparent that the pin 55 abuts against the edge of the vertical channel or slot 62, and causes the window 12 to move to the right or rearwardly in a horizontal direction into the runway 14^a, thereby to provide the ventilating opening V'. During this movement the finger 50 in cooperation with the pin 64 prevents retrograde movement of the window and the pin 58 on the arm 26^a moves forwardly along the inclined portion 60 of its guide channel. The pin 58 supports the forward end of the window during its transverse movement and the inclined portion 60 of the slot compensates for the swinging movement of the pin 58. When the window has completed its horizontal movement the pin 55 is disposed in the lower end portion of the slot 62 in position to move along the horizontal channel 56. When the pin 55 is in that position the pin 58 is disposed in the rear end of the horizontal channel 59.

Upon further swinging movement of the regulator arms away from each other, the window 12 is caused to move downwardly, the pins 55 and 58 moving along their respective channels. This downward movement continues until the window 12 reaches the upper end of the downwardly inclined portion 15 of the runway 14^a, whereupon the cam abutment 53 on the regulator arm 26^a abuts against the pin 66, thereby imparting horizontal downwardly and forwardly inclined movement to the window 12. During this movement the finger 49 moving with the regulator arm 25^a engages the pin 64, the curvature of the contacting surface of the finger 49 being such as to prevent rearward shifting movement of the window after the camming action of the abutment cam 53 and until the rear edge of the window has entered the runway portion 16^a. Thereafter the regulator arms function in the usual manner to lower the window in a straight vertical path.

It will be understood that upon reversal of the direction of movement of the regulator arms 25^a and 26^a the abutment cam 54 engages the pin 67, thereby imparting rearward movement to the window as it travels upwardly until it has passed the inclined runway 15^a, and during this movement the abutment cam 53 rides over its pin 66. It will be understood that the remaining operation to complete the raising of the window and moving the same forwardly to close the ventilating slot V' is a reversal of the operation above described.

When it is desired to disengage the window and its rail 57 from the regulator arms, the arms are moved to the position in which the pins 55 and 58 register respectively with the enlarged portions 63 and 64 of the slotted channels. These openings are sufficient to enable the rail 57 to be swung laterally clear of the pins. The pin 65, which is detachably mounted on the rail, must be removed to afford the necessary movement to the arm 25^a for this purpose.

It is to be understood that numerous changes

in details of construction, arrangement and operation may be effected without departing from the spirit of the invention, especially as defined in the appended claims.

I claim:

1. Regulator mechanism for a window glass mounted in a window opening for successive vertical and horizontal movements in its plane, comprising a retainer member at the lower edge of the glass, a pair of swinging regulator arms, one of said arms and said member having cooperating cam means for shifting the glass in opposite directions longitudinally of the vehicle during the vertical travel of the glass, the other of said arms and said retainer member having cooperating means for shifting the glass edgewise in opposite directions into and out of position to provide a ventilating opening at one upright edge of the glass when the latter is substantially fully raised.

2. Regulator mechanism for a window glass mounted in a vehicle body window opening, comprising a retainer member at the lower edge of the glass, a pair of swinging regulator arms, one of said arms and said member having cooperating cam means for shifting the glass in opposite directions longitudinally of the vehicle during the vertical travel of the glass, the other of said arms and said retainer member having cooperating means for shifting the glass longitudinally in opposite directions into and out of position to provide a ventilating opening at the forward edge of the glass when the latter is substantially fully raised, and one of said arms having a cam extending between the arms when raised and co-operable with a part on said retainer member for blocking the window glass against longitudinal movement in predetermined elevated positions thereof.

3. A regulator mechanism for a window glass mounted in a vehicle body window opening for successive vertical and horizontal movements in its plane, comprising a retainer member at the lower edge of the glass, a pair of swinging regulator arms, one of said arms and said member having cooperating cam means for shifting the glass in opposite directions longitudinally of the vehicle during the vertical travel of the glass, the other of said arms and said retainer member having cooperating means for shifting the glass longitudinally in opposite directions into and out of position to provide a ventilating opening at the forward edge of the glass when the latter is substantially fully raised, and one of said arms having a pair of cams extending between the arms when raised and successively cooperating with parts on said retainer member for blocking the glass against longitudinal movement in different elevated positions thereof.

4. A regulator mechanism for a window glass mounted in a vehicle body window opening for successive vertical and horizontal movements in its plane, comprising a retainer member at the lower edge of the glass, front and rear swinging regulator arms, said front arm and said member having cooperating cam means for shifting the glass in opposite directions longitudinally of the vehicle during the vertical travel of the glass, and said rear arm and retainer member having cooperating means for shifting the glass edgewise in opposite directions into and out of position to provide a ventilating opening at the forward edge of the glass when the latter is substantially fully raised.

5. A regulator mechanism for a window glass mounted in a vehicle body window opening for

- successive vertical and horizontal movements in its plane, comprising a retainer member at the lower edge of the glass, front and rear swinging regulator arms, said front arm and said member having cooperating cam means for shifting the glass in opposite directions longitudinally of the vehicle during the vertical travel of the glass, said rear arm and retainer member having co-operating means for shifting the glass edgewise 5
- 10 in opposite directions into and out of position to provide a ventilating opening at the forward edge of the glass when the latter is substantially fully raised, and one of said arms having a cam extending between the arms when raised and 15 co-operable with a part on said retainer member for blocking the window glass against longitudinal movement when said glass is in predetermined elevated positions.
6. A regulator mechanism for a window glass 20 mounted in a vehicle body window opening for successive vertical and horizontal movements in its plane, comprising a retainer member at the lower edge of the glass, front and rear swinging regulator arms, said front arm and said member having cooperating cam means for shifting the glass in opposite directions longitudinally of the vehicle during the vertical travel of the glass, said rear arm and retainer member having co-operating means for shifting the glass edgewise 25 30 in opposite directions into and out of position to provide a ventilating opening at the forward edge of the glass when the latter is substantially fully raised, and one of said arms having a pair of cams extending between the arms when raised 35 and successively cooperating with parts on said retainer member for blocking the glass against longitudinal movement in different elevated positions thereof.
7. A regulator mechanism for a window glass 40 mounted in a vehicle body window opening for successive vertical and horizontal movements in its plane, comprising a retainer member at the lower edge of the glass, a pair of swinging regulator arms, one of said arms having a pair of cams, one thereof co-operable with said retainer member for shifting the glass forwardly in its plane during the downward travel of the glass, and the other co-operable with said member for shifting the glass rearwardly in its plane during 45 50 the upward travel of the glass, and means controlled by the other of the arms for shifting the glass in its plane into or out of ventilating position when substantially fully raised.
8. A regulator mechanism for a window glass 55 mounted in a vehicle body window opening for successive vertical and horizontal movements in its plane, comprising a retainer member at the lower edge of the glass, a regulator including a pair of oppositely swinging arms for raising and lowering the glass and also for shifting the glass longitudinally of the vehicle into and out of position to provide a ventilating slot at the forward edge of the glass, and cam means carried by the forward of said arms and co-operable with the 60 65 retainer member for shifting the glass forwardly and rearwardly during the downward and upward travel respectively of the glass, said cam means including a pair of spaced cam surfaces at the outer end of said arm, and a part or parts on said retainer member engageable at predetermined times with said surfaces.
12. In a vehicle body having a window opening and a window glass mounted for successive vertical and horizontal movements in the plane of the glass, regulator mechanism comprising front and rear oppositely swinging arms having devices 50 engageable at the lower edge of the glass for raising and lowering the same, said front arm having cam means separate from said device for shifting the window longitudinally during the vertical travel thereof, and means at the lower edge of said glass and engageable by said device on the rear arm for shifting the glass into or out of ventilating position when the glass is substantially fully raised.
13. In a vehicle body having a window opening 60 and a window glass mounted for successive vertical and horizontal movements in the plane of the glass, regulator mechanism comprising front and rear oppositely swinging arms having devices 65 engageable at the lower edge of the glass for raising and lowering the same, said front arm having cam means separate from said device for shifting the window longitudinally during the vertical travel thereof, means at the lower edge of said glass and engageable by said device on the rear arm for shifting the glass into or out of ventilating position when the glass is substantially fully raised, and cam means carried by said rear arm and co-operable with a part or parts at the lower edge of the glass for blocking the window against 70 75

longitudinal movement by a force applied directly to the glass when the window glass is in raised or substantially raised position.

14. In a vehicle body having a window opening and a window glass mounted for successive vertical and horizontal movements in the plane of the glass, regulator mechanism comprising front and rear oppositely swinging arms having devices engageable at the lower edge of the glass for raising and lowering the same, said front arm having cam means separate from said device for shifting the window longitudinally during the vertical travel thereof, means at the lower edge of said glass and engageable by said device on the rear arm for shifting the glass into or out of ventilating position when the glass is substantially fully raised, and a cam extension projecting between the arms when raised and provided with an extended cam surface engageable with means on the lower edge of the glass for blocking the window against longitudinal movement by a force applied directly to the glass when in raised or substantially raised position.

15. In a vehicle body having a window opening and a window glass mounted for successive vertical and horizontal movements in the plane of the glass, regulator mechanism comprising front and rear oppositely swinging arms for raising and lowering the glass, said mechanism having means for shifting the glass in its plane into and out of position to provide a ventilating slot at the forward edge of the glass, means on the said front arm for shifting the glass longitudinally in opposite directions during the vertical travel of the glass, and a pair of cams offset into different vertical planes and carried by the rear arm for blocking longitudinal movement of the glass when in different raised positions.

16. Regulator mechanism for a window glass mounted for successive vertical and horizontal movements in the plane of the glass, comprising front and rear oppositely swinging arms for rais-

ing and lowering the glass and also for shifting the glass longitudinally and edgewise into or out of position to provide a ventilating slot at the forward upright edge of the glass when in substantially fully raised position, and cam means carried by the forward swinging arm for shifting the glass longitudinally in opposite directions during the vertical travel of the glass.

17. A regulator mechanism for a window glass mounted in a vehicle body window opening, comprising a retainer member at the lower edge of the glass, front and rear swinging regulator arms, said front arm having a pair of cams, one thereof cooperable with said retainer member for shifting the glass forwardly in its plane during the downward travel of the glass, and the other cooperable with said member for shifting the glass rearwardly in its plane during the upward travel of the glass.

18. A regulator mechanism for a window glass mounted in a vehicle body window opening, comprising a retainer member at the lower edge of the glass, front and rear swinging regulator arms, said front arm and said retainer having cooperating cam means for shifting the glass in opposite directions longitudinally of the vehicle during the vertical travel of the glass, said cam means including a pair of spaced cam surfaces, and a stud on said retainer member engageable with said surfaces.

19. In a vehicle body having a window opening and the window glass mounted in said opening, regulator mechanism comprising front and rear oppositely swinging arms for raising and lowering the glass, said mechanism having means on the front arm for shifting the glass longitudinally in opposite directions during the vertical travel of the glass, and a pair of cams offset into different vertical planes and carried by the rear arm for blocking longitudinal movement of the glass when in different raised positions.

BURTON S. FLORADAY.
